UNITED STATES PATENT OFFICE.

LENA JEAN TRIPP, OF HOUSTON, TEXAS.

DESIGN FOR A DOLL.

Application filed May 21, 1926. Serial No. 17,795. Term of patent 14 years.

To all whom it may concern:

Be it known that I, LENA JEAN TRIPP, a citizen of the United States, residing at Houston, in the county of Harris and State of Texas, have invented a new, original, and ornamental Design for Dolls, of which the following is a specification, reference being had to the accompanying drawings, forming a part thereof, in which the figure is a front view of the doll, showing my design, showing an adjacent table in dotted lines.

I claim:

The ornamental design for a doll as shown.

LENA JEAN TRIPP.
